US0D1030682S

(12) **United States Design Patent** (10) Patent No.: **US D1,030,682 S**
(45) Date of Patent: ** Jun. 11, 2024

(54) **FLEXIBLE DUST PLUG FOR A SMALL FORM FACTOR MULTI-FIBER CONNECTOR**

(71) Applicant: **US Conec, Ltd**, Hickory, NC (US)

(72) Inventors: **Jason Higley**, Hickory, NC (US); **Darrell R. Childers**, Hickory, NC (US)

(73) Assignee: **US Conec, Ltd**, Hickory, NC (US)

(**) Term: **15 Years**

(21) Appl. No.: **29/801,061**

(22) Filed: **Jul. 26, 2021**

(51) LOC (14) Cl. **13-03**

(52) U.S. Cl.

USPC **D13/156**

CLAIM

The ornamental design for a flexible dust plug for a small form factor multi-fiber connector, as shown.

DESCRIPTION

FIG. 1 is a top front right perspective view showing our new design for a flexible dust plug for a small form factor multi-fiber connector;

FIG. 2 is a rear elevational view thereof;

FIG. 3 is a front elevational view thereof;

FIG. 4 is a left side elevational view thereof, the right side being a mirror image;

FIG. 5 is a top plan view thereof; and,

FIG. 6 is a bottom plan view thereof.
